Primary Examiner — Rashida C. Walshon(74) Attorney, Agent, or Firm — LOZA & LOZA LLP;
Joseph G. Swan(57) CLAIM

The ornamental design for a shoe upper as shown and described.

DESCRIPTION

The sole FIGURE is a front elevational view of a shoe upper, showing my new design.

The portions of the shoe upper shown in broken lines are solely for the purpose of illustrating environment and form no part of the claimed design.
